DESIGN FOR A CASE FOR RANGE TIMERS

Frederick Lux and William A. Hersey, Waterbury, Conn., assignors to The Lux Clock Manufacturing Company, Inc., Waterbury, Conn., a corporation of Connecticut

Application January 21, 1939, Serial No. 82,518

Term of patent 7 years

To all whom it may concern:

Be it known that we, Frederick Lux and William A. Hersey, both citizens of the United States, residing in Waterbury, in the county of New Haven and State of Connecticut, have invented a new, original, and ornamental Design for a Case for Range Timers, of which the following is a specification, reference being had to the accompanying drawing, forming part thereof, in which

Fig. 1 is a front elevational view of a case for range timers embodying our design;

Fig. 2 is a top plan view of the same; and
Fig. 3 is a side elevational view thereof.

We claim:

The ornamental design for a case for range timers, substantially as shown.

FREDERICK LUX.
WILLIAM A. HERSEY.
